UNITED STATES PATENT OFFICE.

WALTER F. ROESKE, OF CHICAGO, ILLINOIS.

LOCK FOR THREADED DEVICES.

Application filed February 10, 1921. Serial No. 443,780.

To all whom it may concern:

Be it known that I, WALTER F. ROESKE, a citizen of the United States, residing at Chicago, in the county of Cook and State of Illinois, have invented certain new and useful Improvements in Locks for Threaded Devices, of which the following is a specification.

My invention relates to locking devices for caps or other articles applied to threaded nozzles and consists in providing the cap with key controlled elements by means of which rotation of the cap on the nozzle may be prevented.

The object of my invention is to prevent unauthorized removal of a cap, or of any attachment secured to the cap, from the nozzle. A familiar application of my invention is to the nozzles of automobile radiators, especially those which are equipped with thermal indicating devices or with emblems of value which, at present, are easily stolen from the car, and in the accompanying drawings I have illustrated my invention as applied to a radiator cap.

Fig. 1 is an elevation of a radiator nozzle equipped with my improved cap and having a temperature indicator formed integrally therewith and showing the key which controls the cap inserted therein.

Fig. 2 is a vertical, transverse section through the cap taken on the line 2—2 of Fig. 1 and showing the locking device in unlocked position.

Fig. 3 is a similar section taken at right angles to the section shown in Fig. 2 on the line 3—3 of Fig. 2.

Fig. 4 illustrates the various parts of the lock separated from each other but facing each other as when assembled.

The remaining figures illustrate a modification of my invention in which—

Fig. 5 corresponds to Fig. 2 but showing the cap locked in position on a nozzle.

Fig. 6 is a section similar to Fig. 5 but showing the cap unlocked.

Fig. 7 is a partial section taken on the line 7—7 of Fig. 5 showing the key controlling elements.

Fig. 8 illustrates the various parts of the modified cap separated from each other but facing each other as when assembled.

Fig. 9 shows the nozzle and a cooperating locking element adapted to be mounted thereon.

Fig. 10 is a bottom view of the cap assembled and

Fig. 11 is a bottom view of the cooperating element which must be mounted on the nozzle.

In my preferred form, as illustrated in Figs. 1 to 4, a cap 1 is provided with a cylinder lock 2, the cam finger 3 of which, when the lock is in locked position, extends below the inner surface of the top of cap 1 as shown in Figs. 2 and 3, and, when the lock is in unlocked position, finger 3 is turned so as to be retracted above the inner surface of the top of the cap. The inner face of the cap is provided with spaced teeth 4 and 5 which form opposed stops. At the lower edge of the cap is a fixed ring 6 provided with internal threads 7. Adjacent the inner surface of the top of the cap is a clutch disk 8, the upper face of which is provided with a tooth 9 adapted to engage tooth 5 on the cap.

Below disk 8 is a shell 10 loosely fitting within cap 1 and provided on its upper face with projections 11, and on its inside wall with threads 7a. A spring 12 is located between disk 8 and shell 10 and is adapted to thrust the former upwardly. The spring 12 and disk 8 are provided with holes 13 and 14 respectively to accommodate projections 11 on shell 10. When the parts are assembled these projections 11 are adjacent the inner surface of the top of cap 1 and one of them will be positioned between teeth 4 and 5. The two additional stops 11 have no operative function and are provided to facilitate assembly. A spacing washer 15 is placed between shell 10 and ring 6.

When the parts shown in Fig. 4 are assembled and the lock is turned to unlocking position one of the projections 11 on shell 10 will engage tooth 4 on cap 1 and at the same time tooth 9 on disk 8 will engage tooth 5 on cap 1 thus holding shell 10 non-rotatably in cap 1. The annular ring 6 must be so assembled with cap 1 that its threads 7 form a continuation of threads 7a on shell 10 when the latter is secured as above described. It is obvious that under these circumstances the cap may be rotated in either direction upon a nozzle in the usual manner.

If the key A be turned to set the lock in locked position, turning finger 3 to the position shown in Figs. 2 and 3, disk 8 will

be thereby moved, against the pressure of spring 12, away from the inner surface of cap 1 and its tooth 9 will be disengaged from tooth 5. This will not affect the engagement of projection 11 and tooth 4 nor, consequently, the screwing on movement of the cap to the right, but if a screwing off movement to the left is attempted, the disengagement of teeth 9 and 5 will permit relative rotation of the shell in the cap and will result in a disalignment or discontinuance of threads 7 and 7'. The friction between threads 7 and the nozzle threads could be made sufficient to produce this relative rotation or it may be advisable or even necessary to provide additional friction such as would be produced by screwing the nozzle right against the inner face of shell 10. It is obvious that such rotation of the cap will now result in a lock-nut operation of shell 10 and the annular ring 6 and the greater force applied to unscrew the cap the tighter the latter will be locked to the nozzle to resist left hand rotation. It will be understood that a very slight rotation of cap 1 under these circumstances will result in its being locked, the result taking place before stop 11 engages tooth 5. At any time, the cap may be again rotated to the right so as to bring tooth 4 against the projection 11 and, if finger 3 is turned to release disk 8, spring 12 will thrust the latter up so that tooth 9 engages tooth 5 and the shell may be unscrewed from the nozzle.

In the modification shown in Figs. 5 to 11 the nozzle 16 is equipped with a non-rotatable ratchet 17 having upwardly facing, radially formed teeth. The cap 18 is provided with a member 19 having downwardly extending pawl teeth 20 adapted to engage the teeth of ratchet 17. Below member 19 is a cover 21 having arcuate openings 22 adapted to permit teeth 20 of member 19 to project therethrough. A carrier 23 is secured to the inner face of the top of cap 18 and supports cover 21 and member 19. Cap 18 mounts a cylinder lock 24, the cam finger 25 of which projects below the inner face of the top of the cap and engages a notch 26 in cover 21. Member 19 is provided with a notch 27 so wide that member 19 is not affected by movement of finger 25. When finger 25 is moved by means of key B from the position shown in Fig. 5 to the position shown in Fig. 6 and vice versa it will rotate cover 21 to the left and back again. Member 19 is held against rotation relative to the cap by the engagement of notches 28 with elements 29 on carrier 23.

The teeth 20 of member 19 project through openings 22 in cover 21 only when the latter is at its extreme right hand position as shown in Fig. 6. When the cover is turned to its left hand position, it is drawn

over teeth 20 and prevents engagement of the latter with the teeth of ratchet 17. A spring 30 presses downwardly on member 19 so as to thrust teeth 20 through openings 22 when cover 21 is so positioned as to align the openings with teeth 20.

It is obvious that when teeth 20 are projecting below cover 21, they will engage ratchet 17 and prevent unscrewing of the cap but when the lock finger 25 is turned to cover up teeth 20 the smooth lower surface of cover 21 is presented to ratchet 17 and the cap may be freely unscrewed.

I am aware that various other modifications of my invention may be made without departing from the principle thereof and I contemplate the usual substitution of equivalent elements in the commercial development of my invention.

I claim:

1. In a nozzle cap, a threaded portion fixed thereto, a relatively rotatable threaded portion normally secured in a position in which it forms a continuation of said first mentioned portion, and key controlled means for releasing said rotatable portion to permit same to move to a position in which it does not form a continuation of said first mentioned portion.

2. In a nozzle cap, a fixed portion having a thread, a rotatable shell within the cap having a similar thread the threads on the fixed portion and on the shell being continuous in one position of the shell and discontinuous when the shell is otherwise positioned, elements normally holding said shell in said first mentioned position and means for rendering said elements ineffective.

3. In a nozzle cap, an integral portion having an interior thread, a relatively-rotatable section having an interior thread adapted, when in a predetermined position, to form a continuation of said first mentioned thread, and a key controlled element adapted to secure said section in said position.

4. In a nozzle cap, continuously threaded elements, angularly movable relative to each other to a position in which they are not continuously threaded and key controlled means for securing such elements against such relative movement.

5. In a locking device, continuously threaded elements angularly movable relative to each other to a position in which they are not continuously threaded, in which position they form a lock nut, and relatively movable means for securing said elements against such relative movement to release said lock nut.

6. In a nozzle cap, a portion fixed thereto and having threads, a relatively movable member having threads adapted, when said member is in a predetermined position, to form a continuation of said first mentioned

- threads, opposed teeth on said cap, an element on said member adapted to be engaged by one of said teeth when said member is in said position and whereby said member may
- 5 be rotated in a right hand direction, a retractable element on said member adapted when not retracted to be engaged by the other of said teeth when said member is in said position and whereby said member may
- 10 be rotated in a left hand direction, and a lock finger normally holding said member in retracted position and adapted to be operated to advance said retractable element to tooth engaging position.
- 15 7. In a nozzle cap, a portion fixed thereto and having threads, a relatively movable member having threads adapted, when said member is in a predetermined position, to form a continuation of said first mentioned threads, opposed teeth on said cap, an element on said member adapted to be engaged by one of said teeth when said member is in said position and whereby said member may be rotated in a right hand direction, a retractable element on said member adapted 20 when not retracted to be engaged by the other of said teeth when said member is in said position and whereby said member may be rotated in a left hand direction, and key controlled means normally holding said 25 member in retracted position.

WALTER F. ROESKE.
